Primary Examiner — Caron D Veynar*Assistant Examiner* — Abraham Bahta(74) *Attorney, Agent, or Firm* — Christopher Wood; Daniel Eisenberg; Premier Law Group, PLLC(57) **CLAIM**

The ornamental design for a casualty care form, as shown and described.

DESCRIPTION

FIG. 1 is a front view of the casualty care form showing my new design; and,

FIG. 2 is a rear view thereof.

It is understood that the sides may be of no substantial thickness. The broken lines showing are for illustrative purposes only and form no part of the claimed design or a specified embodiment thereof.

1 Claim, 2 Drawing Sheets
